UNITED STATES PATENT OFFICE.

WILLIAM NELSON McCOMB, OF NEW YORK, N. Y.

LIGHT-SHIELD.

1,050,967.

Specification of Letters Patent. Patented Jan. 21, 1913.

Application filed November 22, 1910. Serial No. 593,604.

To all whom it may concern:

Be it known that I, WILLIAM N. McCOMB, a citizen of the United States, and a resident of the borough of Manhattan, New York city, in the county of New York and State of New York, have invented certain new and useful Improvements in Light-Shields, of which the following is a specification.

10 My invention relates to improvements in light shields, generally, and in particular to shields for incandescent lamps.

A great many colored lamps are in use at the present time in electric signs and other places. The color effect for these lamps is usually obtained either by making the lamps of colored glass or by coating the lamps with a coloring solution. Both these methods are objectionable—colored glass lamps are too expensive, and the coloring matter, due to the expansion and contraction of the lamps, as well as the action of the weather, usually fades, and soon wears off. Still another method has been used to some extent—this is shown in Patent No. 794,296, and consists of a glass cap fitted over the end of the lamp and held in place by spring arms engaging the body of the lamp. Even this method is open to many serious objections—the glass caps are expensive to make and as they are extremely frail, the breaking loss is considerable; brass is the only material so far found practicable for the spring arms and under the heating action of the lamp the spring arms soon lose their resiliency, permitting the caps to become loosened and finally disengaged from the lamp.

It is the object of my invention to overcome these various objections and this I do by attaching a color shield to the lamp by mechanical means in such a way that it cannot become loosened or accidentally detached from the lamp.

45 Another feature of improvement consists in making the cap of a cheaper and less breakable material than glass, such as pyrolylin.

In its preferred form the invention consists of a color shield, which is secured in place upon the lamp by means of a member fitted over the opposite end of the lamp than that to which the shield is applied, the said member being of less diameter than the greatest diameter of the lamp, and a means of connection between the member and the

color shield. The color shield may be in the form of a close fitting cap, preferably of slightly less diameter than the greatest diameter of the lamp, so as to hug the end 60 of the lamp.

Various other objects and features of the invention will appear as the specification proceeds.

I have illustrated in the accompanying 65 drawings several preferred forms of the invention, but it will be understood that various changes and modifications may be made therein without departing from the spirit and scope of the invention.

70 In the drawings: Figure 1 is a side elevation of the invention in its simplest form, as applied to a lamp bulb, certain of the parts being broken away and shown in section. Fig. 2 is a like view of a slightly different form of the invention in which the shield entirely incloses the lamp. Figs. 3 and 4 illustrate different ways of securing the shield in place.

75 Like reference characters refer to like 80 parts throughout the several views.

My improved light shield may, and preferably does consist of a close fitting cap 1, which, as shown in Figs. 1 to 4, is engaged on the end of the lamp bulb 2. This cap 85 may, if desired, be made of glass or similar transparent or translucent material. For this purpose, however, I prefer to use a cheaper and more durable material such as pyrolylin. An infinite variety of colors may 90 be obtained in this material and a cap made of this material possesses a degree of resiliency and flexibility which is desirable. The cap is preferably made of a slightly 95 less diameter than the greatest diameter of the lamp so as to closely hug the end of the lamp. The cap is preferably secured in place by being attached to a member which is fitted over the smaller end of the lamp and is of a diameter less than the greatest 100 diameter of the lamp to prevent its slipping over the head of the lamp. This member may be either in the form of a collar 3, as illustrated in Figs. 1, 3, and 4 or if it is desired to shield the entire globe, this member 105 may be in the shape of a jacket 4, inclosing the smaller end of the globe, as in Fig. 2. Various means of connection between the cap and the securing member may be employed. Preferably, however, these two 110 parts are secured together by means of a bead 5 on one of the parts, which interlocks

with a corresponding flange or bead 6 on the other member, as illustrated in the first two figures. Thus in the forms shown in Figs. 1 and 2 the cap would be applied to the end 5 of the lamp, and the collar or the jacket, as the case may be, would then be slipped over the smaller or inner end of the lamp, and by bringing the flange on the one part over the bead on the other part; the meeting 10 edges would interlock to secure the cap in place. The annular securing member may be made of the same material as the cap, or, if found desirable, this securing member could be made of fiberoid, metal or other 15 material.

As the lamp globes sometimes vary in size, an adjustable connection may sometimes be found desirable. This may be attained, as in Fig. 3, by providing openings 7 in the 20 marginal portions of the collar or jacket, as the case may be, through which a wire 8 or other securing medium is passed. In this way the cap may be connected by lacing to the collar or jacket. This method would 25 be of advantage where the end portions of old burnt out colored globes are used as the caps. Another form of adjustable connection between the cap and the annular securing member is illustrated in Fig. 4. In 30 this case one of the parts is provided with a lug or pin 9 which is received in an inclined slot 10 in the other part. The inclination of this slot permits of the desired degree of adjustment between the two parts.

35 What is claimed, is:

1. A color cap adapted to closely fit the end of an incandescent lamp, and means for securing said cap in place, comprising a member fitted over the smaller end of the 40 lamp, said member being of less diameter than the greatest diameter of the lamp, and a means of connection between said member and the cap.

2. A color cap adapted to closely fit the 45 end of an incandescent lamp, and means for securing said cap in place comprising a collar of lesser diameter than the greatest diameter of the lamp, fitted over the smaller end of the lamp, and connection between 50 said collar and the cap.

3. A color cap adapted to closely fit the end of an incandescent lamp, and a member fitted over the smaller end of the lamp, said member being of lesser diameter than the greatest diameter of the lamp and said member and the cap having interlocking parts. 55

4. A color cap adapted to closely fit the end of an incandescent lamp, and a member fitted over the smaller end of the lamp, said member being of lesser diameter than 60 the greatest diameter of the lamp and said member and the cap having interlocking parts one of which parts is adapted to be yieldingly sprung over the other so as to maintain the parts interlocked. 65

5. A color cap adapted to fit the end of an incandescent lamp, and means for securing said cap in place comprising a collar applied to the smaller end of the lamp and of a diameter less than the greatest diameter 70 of the lamp, the said member and the cap having interlocking parts, one of which is adapted to be expanded to engage over the other.

6. The combination with an incandescent lamp, of a divided shell, the parts of which 75 are adapted to be fitted over the opposite ends of the lamp, the meeting edges of the parts making interlocking engagement so as to secure the shell in place.

7. A covering for incandescent lamps 80 comprising a shell divided into two parts, which parts are designed to be fitted over the opposite ends of the lamp, and means carried by the meeting edges of the parts for securing said parts together. 85

8. A light shield for incandescent lamps comprising a collar applied to the lamp bulb on one side of the greatest diameter thereof, said collar being of a lesser diameter than the greatest diameter of the lamp, 90 and a color cap applied to the lamp on the opposite side of the greatest diameter and having connection with the said collar.

Signed at New York city in the county of New York and State of New York this 95 19th day of November A. D. 1910.

WILLIAM NELSON McCOMB.
